(57) **CLAIM**

The ornamental design for a multifunction support for mobile device, as shown and described.

DESCRIPTION

FIG. 1 is a front elevational view of a multifunction support for mobile device showing my new design;

FIG. 2 is a rear elevational view thereof;

FIG. 3 is a top plan view thereof;

FIG. 4 is a bottom plan view thereof; and

FIG. 5 is a right side elevational view thereof;

FIG. 6 is a left side elevational view thereof; and,

FIG. 7 is a sectional view thereof, which is taken at line 7-7 in FIG. 1.

The even dashed broken lines in FIG. 1 depict portions of the multifunction support for mobile device that form no part of the claimed design. The dot-dash broken lines in FIG. 1 depict the sectional view indications, which is shown in FIG. 7, and form no part of the claimed design.

1 Claim, 6 Drawing Sheets
